UNITED STATES PATENT OFFICE

158,150

REFRIGERATOR CABINET

Carl W. Sundberg and Montgomery Ferar, Detroit, Mich., assignors to Seeger Refrigerator Company, St. Paul, Minn., a corporation of Minnesota

Application May 28, 1949, Serial No. 2,932

Term of patent 3½ years

(Cl. D67—3)

To all whom it may concern:

Be it known that we, Carl W. Sundberg and Montgomery Ferar, citizens of the United States and residents of Detroit, in the county of Wayne and State of Michigan, have invented a new, original, and ornamental Design for a Refrigerator Cabinet, of which the following is a specification, reference being had to the accompanying drawing, forming a part thereof.

Fig. 1 is a front perspective view of a refrigerator cabinet embodying our new design;

Fig. 2 is a reduced side elevation of the same; and

Figs. 3, 4 and 5 are surface contour section lines of the front and sides taken along the lines 3—3, 4—4 and 5—5, respectively of Fig. 1.

The side not shown in the drawing is similar

to the side shown in Fig. 2 and the top, bottom and rear are plain.

We claim:

The ornamental design for a refrigerator cabinet, substantially as shown and described.

CARL W. SUNDBERG.
MONTGOMERY FERAR.
